RUHR, GERMANY.

AXLE-RECORDING DEVICE FOR RAILWAYS.

1,421,500.

Specification of Letters Patent.

Patented July 4, 1922.

Application filed February 14, 1921. Serial No. 445,046.

To all whom it may concern:

Be it known that we, WERNER KOLBE, residing at Essen-on-the-Ruhr, and JOHANNES FRITZEN, residing at Essen-on-the-Ruhr, 5 Prussia, Germany, both citizens of the Republic of Germany, have invented a certain new and useful Improvement in Axle-Recording Devices for Railways, of which the following is a specification.

10 This invention relates to devices destined to record the axles passing across a railway-line, which will not only indicate the number of axles and the direction of running thereof, but also the axle pressure and the 15 time at which the train passes. The object of the invention is to establish a device of the aforesaid character, excelling by the fact of being capable of supplying absolutely reliable and correct indications for 20 every travelling speed.

One embodiment of the subject matter of the invention is shown by way of example in the annexed drawings in which—

25 Fig. 1 is a top view of the part of the device arranged on the rails of a railway track,

Fig. 2 a sectional view along line 2—2 in Fig. 1, looking from the left,

Figs. 3 to 7 sectional views along lines 3—3, 4—4, 5—5, 6—6, 7—7, respectively, in 30 Fig. 1, looking in the direction of the arrow *w*,

Fig. 8 a diagram showing the electrical connections and the recording mechanism, and

35 Fig. 9 a diagram drawn by the recording mechanism.

First of all that part of the improved device will be described which is arranged on the rails of a railway track.

40 On the sleepers *A* of a railway track running to a station, there are secured two oppositely disposed plates *B* and *C*, the major part of each of which is lodged beyond the rails *D* and *D*¹, while the minor part of 45 each is lodged thereunder. By means of a pin *b*¹ disposed in parallel to the rails *D*, *D*¹ there is swivelled to the plate *B* a flap *E* secured against rotation in the direction indicated by arrow *x* (Figs. 3 and 50 4) by a pair of check surfaces *b*² *e*¹. The flap *E* faces the rail *D* and extends with its unattached end, shaped to match the head of the rail, in a recess *d*² of said head. The flap *E* rests on a bolt *F* adapted to be dis-

placed in a perpendicular direction. This 55 bolt moves in a spring pocket *b*³ secured to the plate *B* and is acted upon by an initially tensioned spring *G*. To the underside of the flap *E* there is arranged an electric contact member *e*² which, on the flap *E* oscillating in the direction counter to that indicated by arrow *x*, will strike against a contact member *b*⁴ mounted on the plate *B*. By aid of a pin *c*¹ disposed in parallel to the rails *D*, *D*¹ there are mounted on the plate 60 *C* in juxtaposition two flaps *H* and *J*, each secured against rotation in the direction denoted by arrow *y* (Figs. 5 and 7) by a pair of check surfaces *c*² *h*¹ and *c*² *j*¹, respectively. The flaps *H* and *J* in their 65 turn face the rail *D*¹ and project with their unattached ends shaped to match the head of the rail, in a suitable long recess *d*³ formed in the head of the rail *D*¹. The said head is provided with a trough-shaped 70 sunken portion *d*⁴ in the section of the rail *D*¹ adjoining the plate *H* and this in the manner disclosed in Figs. 1, 2, 6 and 7. The flaps *H* and *J* rest on bolts *K* and *M* respectively, adapted to be displaced in the 75 perpendicular sense. These bolts move in spring-pockets *c*³ and *c*⁴ mounted on the plate *C*, and are subjected to the action of initially tensioned springs *N* and *P*, respectively. The spring *N* is substantially 80 more powerful than the springs *G* and *P*. To the underside of the flaps *H* and *J* there are fixed electric contact members *h*² and *j*² which, when the flaps *H* and *J* are rocked in a direction contrary to that denoted by 85 the arrow *y*, make contact with the electric contact members *c*⁵ and *c*⁶, for their part fixed to the plate *C*. Within a space remote from the parts so far referred to, say, for instance, the station-masters room, 90 there is arranged an electromagnetically operated recording mechanism. This recording mechanism, comprises a revolving recording drum *Q* adapted to be rotated jerkwise by means of an electromagnetically 95 controlled feed mechanism. The ends of the magnet winding *r*¹ appertaining to this feed mechanism communicate with a source of electric power *R* by intervention of the contact members *i*² *c*⁶ already referred to. Two 100 recording pens *S* and *S*¹ of different lengths and pivotally fixed to a support *s*² are 105 adapted to co-operate with the shell sur-

face of said drum Q, the points of which pens touch the shell surface of said drum at points disposed on two adjoining generatrices of said surface. By aid of magnet 5 windings r^2 and r^3 the recording pens S and S^1 may obtain a rocking motion which will enable them to draw a short line on the recording drum which line runs in the direction of a generatrix of the shell 10 surface of said drum. The support s^2 is mounted to shift but not to rotate, on a spindle t^1 for its part adapted to rotate at a uniform speed by the intervention of a clockwork T. The magnet windings r^2 and r^3 communicate with the source of electric power R by aid of the contact members e^2 15 and h^2 c^5 , respectively.

In considering the manner of operation of the hereinbefore described device, let it be 20 assumed that the several parts be in the positions indicated in the drawings and that the spindle t^1 is rotated at a uniform speed by the clockwork in such a manner that the support s^2 will slowly displace itself in the 25 direction indicated by the arrow z . The two recording pens S and S^1 will consequently come to mark two time-indicating lines q^1 , q^2 on the surface of the recording drum; these lines running primarily in the direction of the generatrices of said shell surface, see Fig. 9. The time-lines q^1 and q^2 indicate that no cars of any kind whatsoever have run across the track D D¹ during the 30 interval of time from 7.55 to 8.00. Let it now further be assumed that at 8 o'clock a train comprising four loaded, seven unloaded and five loaded axles is passing across the railway track D D¹ in the direction denoted by the arrow v (Fig. 8). The front axle 35 of this train will then pass with one of its wheels primarily across the flap J. The spring P appertaining to this flap is so dimensioned that the said flap will be rocked in a direction counter to that indicated by the arrow y , by either loaded or unloaded 40 axle for such an extent, that the contact members i^2 c^6 will make contact. As a result, the circuit embodying the magnet winding r^4 will be closed and the feed mechanism 45 controlled by this winding will rotate the recording drum Q for a slight angle. The rotation of the recording drum Q causes the direction of the time-lines q^1 and q^2 marked by the recording pens S and S^1 to be 50 rectangularly deflected so that they will now run in the direction of the circumference of the drum. Shortly after the front axle has passed across the flap J, both wheels of this same axle pass across the oppositely 55 disposed flaps E and H. In this case too the springs G and N appertaining to these two flaps are in their turn so dimensioned that the flap H will be rocked only by loaded, the flap E however by both loaded and 60 unloaded axles and for such an extent in a

direction counter to that indicated by arrows y and x that the contact members h^2 c^5 and e^2 b^4 , respectively, will make contact. The wheels of the front axle, which as already stated is loaded, will in passing over 65 the flaps E and H cause these to be so far rocked counter to the direction indicated by arrows x and y that the members e^2 b^4 and h^2 c^5 , respectively, will temporarily make contact. In this event, the flap E will be depressed for such an extent that the surface of the portion thereof touched by the rim of the wheel will come to lie flush with the surface of the head of the rail, while the flap H will be angularly rotated so that when this 70 flap is in its lowermost position, the surface thereof touched by the rim of the wheel will for its part lie perfectly flush with the bottom of the trough-shaped sunken portion d^4 of the rail D¹. Hence, the wheel passing 75 across the flap H will slightly sink downward in traversing the trough-shaped sunken portion d^4 . The members e^2 b^4 and h^2 c^5 having, as said, temporarily made contact, the circuits embodying the magnet windings r^2 and r^3 will come to be closed 80 for a short time. Acting under the influence of the current which then traverses the magnet windings r^2 and r^3 , the recording pens S and S^1 now each make a stroke q^3 and q^4 , 85 respectively, on the recording drum Q. The arrangement devised is such that the strokes q^3 and q^4 produced in consequence of the excitation of the magnet windings r^2 and r^3 will be disposed at right angles to the section of the time-lines q^1 and q^2 lying in parallel to the circumference of the drum. Directly after the aforesaid operations have 90 been effected, the second and likewise loaded axle passes, first with its one wheel across the flap J and then with both wheels across the flaps E and H. The result is that the same operations will now also repeat themselves on the recording drum Q, that is to say, by this drum now in rotation, the time-lines q^1 and q^2 are first of all each prolonged 95 for a little extent in the peripheral direction of the drum, whereupon the recording pens S S^1 make two strokes q^5 and q^6 . This will also be the case as the third 100 and the fourth loaded axle passes with its wheels across the flaps J and E and H, respectively. The time-lines are each time first prolonged for a little extent, whereupon the strokes q^7 to q^{10} are made on the 105 recording drum by the recording-pens S S^1 . As the seven unloaded axles now successively pass across the flaps J and E, H, respectively, the aforesaid operations are in 110 general repeated. The sole difference is that the flap H is not rocked in a direction counter to that indicated by the arrow y as the wheels of the unloaded axles pass across it. On the contrary, the wheels of the unloaded 115 axles—owing to the spring N being consider- 120

125 130

ably stronger than its companion springs—pass across the flap H without compressing said spring N. Hence, no contact is made by the contact members h^2 and c^5 and the 5 magnet winding r^3 consequently remains un-excited. As each unloaded axle passes across the track, the time-lines on the recording drum are therefore first prolonged for a small extent and then the excitation 10 of the magnet winding r^2 resulting from the depression of the flap E causes the recording pens to mark the strokes q^{11} to q^{17} , which strokes correspond to the marks q^3 , q^6 , q^7 , q^9 on the recording drum. On the other hand, 15 no strokes corresponding to the strokes q^4 , q^6 , q^8 , q^{10} come to be made. The operations effected as the succeeding five loaded axles now pass across the track correspond exactly to those carried out and hereinbefore described 20 in connection with the passing of the first four loaded axles of the train. On the recording drum there are thus produced, in succession and each time after the time-lines q^1 and q^2 have been prolonged 25 for a slight extent, the strokes q^{18} to q^{27} . After the last wheel of the train passes, all the parts of the device arranged on the rails again return into their initial position shown in the drawing, and only the support s^2 is 30 moved by the clockwork T in the direction of the arrow z . The time-lines q^1 , q^2 are therefore again rectangularly deflected the instant the last axle has passed across the flaps E and H, and now once more continue 35 to run in the direction of the generatrices of the recording drum. The time-lines thereby indicate that in the interval of time from 8.00 to about 8.17 no cars have traversed the particular section of the track where the 40 device is mounted.

Let it now once more be assumed that at this time, i. e., 8.17, a train composed of eight loaded, six unloaded and two loaded axles, is passing across the device in the direction counter to that indicated by the arrow v in Fig. 8. The operations in connection with the depressing of the flaps E and H, as also J will now be the same as those already hereinbefore described, and, 45 in consequence, the flaps E and J come to be depressed by both the loaded as well as the unloaded axles, while the flap H is rocked in the sense counter to arrow y (Figs. 5 to 7) only as the loaded axles pass across it. In this case, however, the wheels first depress the flaps E and H and then only the flap J. The result is that, owing to the 50 magnet windings r^2 and r^3 , respectively, being now excited before the recording drum Q has been set in rotation, the recording pens primarily make the strokes q^{28} and q^{29} , respectively, and only then—as the magnet winding r^1 comes to be excited—prolong the time-lines q^1 and q^2 for a slight extent in 55 the peripheral direction. The ends of the

sections of the time-lines running in the peripheral direction of the recording drum, are therefore each now disposed for the length of their respective prolongation to the rear of the last strokes q^{28} , q^{29} , recorded, 70 whereas in the case of the train running in the direction denoted by arrow v , the ends of the sections of the time-lines drawn in the peripheral direction of the recording drum coincide with the starting points of the strokes q^{26} and q^{27} . After the last wheel has passed across the flap J, all the parts of the device mounted on the rails return into their initial position and the recording pens S and S^1 , acted upon by the support 75 s^2 displacing itself along the spindle t^1 again continue to draw the time-lines in the direction of the generatrices of the recording drum. This will continue until a train again passes across the device in either the one 80 or the other direction.

From the aforesaid it will be readily understood that the strokes marked on one of the time-lines, q^1 , will indicate the sum-total of the axles that have passed across the railway track equipped with the device, while the strokes marked on the opposite time-line, q^2 , indicate how many and which of these said axles were loaded. Owing to the circumstance already mentioned, that the 90 ends of those sections of the time-lines disposed in the peripheral direction of the recording drum, coincide with the last strokes marked thereon (see in particular lines q^{26} , q^{27}) or else extend beyond them, there may, 100 in addition, be ascertained the direction in which the respective train has passed across the device. But besides this, the device will also indicate the time at which each train passed. 105

In the place of a single flap H and a single recording pen S^1 belonging thereto, there may also be arranged a plurality of such flaps with their respective contact members and recording pens, and the arrangement 110 may then be so devised that each of these recording pens will mark a separate time-line and each of said flaps be adapted to bring about a closing of the circuit and therewith cause a line to be marked at right angles to the respective time-line, and this always for a different range of weight. In such a case there would then not only come to be recorded the number of unloaded and loaded cars, but there would in addition be indicated the range of weight within which lies the axle-pressure of each separate axle. 120

Moreover, the fact that, in the described recording device each of the members causing a circuit to be closed can always close 125 only one particular circuit and no more, produces the chief advantage proper to the subject matter of the invention in that it is impossible of a wrong circuit being closed at any time, so that therefore the indications 130

marked on the recording drum will always be absolutely reliable and correct, regardless of the speed at which a train travels across the device.

5 Having now particularly described and ascertained the nature of our said invention and in what manner the same is to be performed, we declare that what we claim is:—

10 1. A recording device for railways comprising two independent electric contact devices positioned adjacent the track rails and adapted to be actuated by different axle pressures of the cars passing over the track, a third contact device also operated by the 15 passage of cars over the track, a recording device comprising an intermittently rotating recording drum and a pair of recording members, means connecting the first mentioned contact devices to the recording members respectively and means connecting the 20 last mentioned contact device to said recording drum.

2. A recording device for railways comprising a pair of electric contact devices 25 disposed on opposite sides of the track and adjacent said rails so as to be operated by the wheels of cars passing over the track, said contact devices being operable by different axle pressures, a third contact device disposed adjacent one rail of the track and operable by the wheels of the car passing over said track, a recording apparatus comprising an intermittently rotatable recording drum and a pair of recording members, 30 said first mentioned contact devices being each connected to one of said recording members, means for displacing said recording members axially of said recording drum at a pre-determined speed and means connecting said third contact device to said recording drum whereby it will be intermittently rotated when its corresponding contact device is caused to function, the functioning of said first mentioned contact devices causing said recording members to 35 function.

3. An axle recording device for railways comprising electric contact devices adapted to be disposed adjacent the rails of said railway, each contact device including a pivoted flap, a power accumulator disposed under said flap, the rails of said railway being formed with a recess to accommodate the edge of said flap, said flap being adapted to 40 be moved against the tension of its corresponding power accumulator by the wheels 45

of a car passing over said railway, electrically operated recording apparatus connected to said contact devices and adapted to function when said contact devices are operated. 60

4. A recording device for railways comprising electric contact devices associated with the rails of said railway so as to be actuated by the wheels of a car passing thereover, each of said contact devices including a pivoted flap, the free end of which is disposed in recesses formed in the rails of said railway, one of said contact devices being operable only by a comparatively 65 greater pressure, the rail adjacent said last contact device being formed with a trough-shaped sunken portion to permit the flap of said contact device to be depressed and an electrically operated recording apparatus 70 connected to said contact devices and operable when said contact devices function. 75

5. A recording device of the class described for railways comprising three contact devices associated with the rails of said railway and disposed so as to be operable by the wheels of a car passing thereover, each contact device comprising a stationary member, a pivoted member, electric contacts carried by said stationary and movable members and adapted to close an electrical circuit when said movable member is depressed, a power accumulator disposed under the movable member of each contact device and tending to normally keep said movable member raised and said contacts out of engagement, the power accumulator of one of said movable members being of greater strength than the others, a recording apparatus comprising a recording drum and a pair of recording members, electrical means connecting one of said contact devices to said drum whereby said drum will be intermittently rotated when said contact device functions and means connecting each one of the other contact devices to a respective recording member, whereby said recording members may be operated when their associated contact devices function. 90 95 100
